OPHTHALMIC MOUNTING

Edward M. Splaine, Southbridge, Mass., assignor to American Optical Company, Southbridge, Mass., a voluntary association of Massachusetts

Application March 1, 1935, Serial No. 8,884

5 Claims. (Cl. 88—47)

This invention relates to securing means and is particularly concerned with means for securing together the ends of split lens holding rims of ophthalmic mountings.

5 Heretofore, difficulty has been experienced in developing securing means for holding together the ends of split rims of ophthalmic mountings. Many factors contribute to the difficulty encountered. In designing such securing means 10 the aesthetic aspect must be considered along with the mechanical details.

A large percentage of ophthalmic mountings are made of filled stock, that is, a relatively inexpensive base metal coated with a precious metal such as gold. Since this type of base metal is highly corrosive, great care must be taken not to break the coating of precious metal which serves to protect the base metal from the corrosive action of perspiration from the wearer's face. The point at which the protective coating is most likely to be broken is where the lens rims are split and have external connecting means. In the prior art devices, the lens rims have been split at the sides adjacent the juncture of the temples and rims. When the rims are so split, the connecting means are well removed from possible attack from perspiration but it is difficult, in such devices to get a very long thread bearing while at the same time retain the desired aesthetic characteristics of the mounting. According to this invention, the rims have been split and the connecting means have been applied near the nasal side of the rims and constructed in such a manner that the connecting means appear to be a part of the bridge. Since the connecting means is necessarily very close to the skin of the wearer, special construction is necessary to eliminate as far as possible any breaking of the precious metal coating on the 40 mounting where corrosion would start.

Accordingly, one of the major objects of this invention is to provide an ophthalmic mounting having means for securing together the ends of the lens holding rims in a manner to overcome the above mentioned difficulties and which will be pleasing to the eye.

Another object of this invention is to provide a novel means for securing together two separable elements.

50 Another object of this invention is to provide an ophthalmic mounting having the ends of the split lens holding rim secured together by means which are simple, inexpensive to manufacture, and yet mechanically strong.

55 A further object of the present invention is to

provide an ophthalmic mounting having split lens holding rims in which the ends of the rims are held together by means which appear to be a part of the bridge when viewed from the front.

5 A still further object of this invention is to provide an ophthalmic mounting of the type described in which the means for securing the ends of the split rims together is tapered off toward the rim in such a manner that the contour thereof harmonizes with the lines of the bridge structure joining the rim.

Another object of this invention is to provide a very long threaded connection for securing the ends of the split rims of an ophthalmic mounting and at the same time retaining harmonious cooperation between the connecting means and the parts of the mounting.

Other objects and advantages of the invention will become apparent from the following description taken in connection with the accompanying drawings, and it will be apparent that many changes may be made in the details of construction and arrangement of parts shown and described without departing from the spirit of the invention as expressed in the accompanying claims.

I, therefore, do not wish to be limited to the exact details shown and described, as the preferred forms only have been shown in the way of illustration.

Referring to the drawings:

Figure I is a front view of an ophthalmic mounting embodying this invention.

Figure II is a partial plan view of the mounting shown in Figure I with the ends of the temples broken away for the purpose of clarity.

Figure III is a detailed sectional view of one form of this invention.

Figures IV to IX, inclusive, are detail sectional views of modifications of Figure III.

Figure X is a side elevational view of Figure IX.

Figure XI is a section of Figure V taken on line XI—XI.

Figure XII is a section taken on line XII—XII of Figure V, and,

Figures XIII and XIV are partial detail views showing the means by which the nose guard arms are secured to the lens rims.

Still referring to the drawings in which subscripts are used for denoting corresponding but dissimilar parts, embodiments of the invention are illustrated in connection with a pair of spectacles comprising a pair of lens rims 16 connected

together by means of a bridge 17 and each of the rims having an oppositely disposed endpiece 18, to which temples 19 are pivotally secured in any well known manner. Nose guards 20 carried on arms 25 which are secured to the back side of the lens rims cooperate with the temples to position the spectacles on the wearer's face. The bridge 17 is shaped so as to blend with the direction lines of the means for connecting the ends of the split rims together, so that the connecting means and bridge appear unitary when viewed from the front. The ends of the split rims carry lugs 21 and 22 and a headed screw 23 is provided to engage both of the lugs to securely hold same together in order to retain the lens 24 in snug engagement with the rim throughout its periphery. The lugs are secured to the lens rim by a hard solder process or in any other suitable manner. A single piece of metal stock having the 20 combined size and form of the two lugs 21 and 22 may be soldered to the lens rim. The metal stock may then be drilled and tapped to receive the body and threaded portion of the screw and the rim and stock may then be cut into as at 16a 25 thus producing a split lens holding rim with lugs secured to each end. The upper lug 21 is similar to the form of the prior art devices, while the lower lug 22 is very much longer whereby a very long screw threaded connection is provided in 30 order to facilitate removal of the lenses. Also the great length of the lower lug precludes any breaking of the contour and consequently the precious metal coating. Since the end of the screw is concealed in the lower lug there are no 35 sharp projections which might cause injury to the wearer and catch the wearer's clothing or interfere with the cleaning of the lenses with a cleaning cloth.

In order that the lines of the bridge and the 40 connecting means shall harmonize the bridge 17 is suitably secured to the lens rim 16 and is provided with portions shaped to blend with the contours of the assembled connecting means.

The bridge extends backward from the juncture 45 with the lens rim and is then looped forward on itself to form portions 17a shaped to fit snugly on either side of the nose of the wearer and to provide clearance for gaining access to the screw from above by means of a suitable tool such as a 50 screw driver, as clearly shown in Fig. II. The bridge extends forward approximately to the plane of the lens rim and then upward forming an offset portion 17b in approximate alignment with the contour of lugs 21 and 22 so that when 55 the mounting is viewed from the front the securing means and the bridge appear to be unitary thus producing a very pleasing appearance.

One of the salient features of this invention is 60 the provision of a very long threaded screw connection for securing the ends of the split rims together without sacrificing the appearance of the ophthalmic mounting. The long threaded connection insures that the ends of the split rims will be maintained in proper alignment while the 65 ends are spread to remove or replace a lens.

One of the preferred embodiments of my novel 70 connecting means is shown in Figure III, in which the lug 21 is secured to the upper end of the split rim and is bored to receive the screw 23. The lug 22 is secured to the lower end of the split lens rim and the outer contour thereof is tapered off 75 toward the lens rim relieving the connection of any abrupt changes in its lower contour. It is to be noted that by tapering off the lower end of the lower lug, a very long thread bearing surface

is obtained and the outer surface is not broken, thereby fully protecting the base metal. The direction lines of the outer contour are made to blend with the offset portions 17b of the bridge to obscure the presence of an external connecting means on the lens rims. In the construction of Figure III, the bore to receive the screw is tapped into the side of the rim so that one side of the screw engages the rim while the opposite side engages the lug 22. Such an arrangement reduces the size of the connecting means and makes a stronger connection by virtue of the fact that the screw engages threads cut into the rim and thereby takes some of the stress normally carried by the soldered connection of the lug 22 to 15 the lens rim.

Furthermore, with such an arrangement the force holding the ends of the lens rim together is applied nearer in line with the periphery of the rim so that the rim will in no way be distorted and will set snugly and engage the lens at all points. In Figure IV the upper end of the rim is notched at 26 and is engaged by the head of the screw thereby further increasing the strength of the joint, by carrying some of the stress normally carried by the connection of the lug to the rim.

As a modification of the embodiment shown in Figure III, the bore to receive the screw 23 may be entirely within the lug as shown in 30 Figures V to X inclusive.

In Figures VI and VII a slightly different modification is shown in which the lower lug has an upwardly extending tubular portion 27 adapted to fit within the bore in the upper lug. The head of the screw 23 is adapted to engage the upper end of the upper lug when the screw is engaged in the screw threaded bore of the lower lug. The tubular portion 27 fitting in the bore in the upper lug maintains the ends of the rim in proper alignment when the lenses are being changed. Also in the modification of Figure VII the lower lug is covered with a thin shield 28 which tapers off against the lens rim and extends up to the top of the upper lug 21d thereby completely hiding the joint between the upper and lower lugs. This thin shield is preferably secured to the lower lug along the outer edge thereof and at its lower end to the lens rim.

The modification of Figure VIII shows the 50 upper lug 21e as being tapered off toward the lens rim in such a manner that when viewed from the front the connection appears to merge directly into the foot of the bridge where it joins the lens rim. The same result may be accomplished by 55 using lugs having surfaces extending at right angles from the lens rims and securing ornamental shields 29, shown in Figures IX and X, on either side of the connection and approximately in a plane with the side of the lens rim so that 60 when viewed from the front the connecting means appears to be unitary with the bridge.

The manner in which the nose guard arms are secured to the lens rim is shown in Figures XIII and XIV. In Figure XIII the nose guard arm has an upwardly extending foot portion attached to the upper portion of the split lens rim while in Figure XIV the arm is shown as having a downwardly extending foot portion secured to the lower portion of the split lens rim. The upwardly or downwardly extending foot provides a greater securing surface with the lens rim.

From the foregoing description it will be readily apparent to one skilled in the art that I have provided a novel connecting means, which is par- 75

ticularly adapted for securing together the ends of a split rim ophthalmic mounting in which a long threaded connection is provided without breaking down the precious metal outer wall of the connecting means on the side thereof towards the face. Said long threaded connection facilitates removing and replacing lenses while at the same time the aesthetic value of the mounting is not sacrificed.

10 Having described my invention I claim:

1. In an ophthalmic mounting having split lens-holding rims, means for securing together the adjacent ends of said rims comprising a lug secured to each end of said rim, a screw having a head engaging one of said lugs and screw threads engaging the other of said lugs and a portion of the corresponding end of said rim between said lug and rim.

2. Connecting means for uniting the meeting ends of separable parts comprising a lug on each of said parts adjacent the meeting ends thereof, one of said lugs having an opening therein and the other of said lugs being of substantial length and having a side wall tapering from its end adjacent the first lug towards its opposite end, said lug having an opening therein alignable with the opening in the first lug and having a threaded bore, said threaded bore being confined within the exposed walls of the lug and the adjacent portion of its associated part and forming a relatively long thread bearing and a screw member in said aligned openings for securing the lugs together, one of the side walls of threaded bore being formed by the associated part and the remainder of said bore being formed by the lug.

3. Connecting means for uniting the meeting ends of separable parts comprising a lug on each of said parts adjacent the meeting ends thereof, one of said lugs having an opening therein and the other of said lugs being formed of solid material of substantial length secured along one of its longitudinal side walls to its respective part and having its opposed side wall tapering from its end adjacent the first lug toward its opposite end, wherein it blends into the part to which it is

secured, said lug having an opening extending therein from its end adjacent the first lug to a point confined within its outer walls and being alignable with the opening in the first lug, and having a threaded bore, said threaded bore being confined within the exposed walls of the lug and forming a relatively long thread bearing and a screw member in said aligned openings for securing the lugs together, the threaded end of said screw being sealed from exposure by the solid 10 walls of the tapered lug when the parts are in secured relation with each other.

4. Connecting means for uniting the meeting ends of separate parts comprising a lug on each of said parts adjacent the meeting ends thereof, one of said lugs being formed of solid material of substantial length secured along one of its longitudinal side walls to its respective part and having its opposed side wall tapering from its end adjacent the first lug toward its opposite end 20 wherein it blends into the part to which it is secured, said lugs being alignable with each other, and means engaging said lugs for securing the same together without piercing the wall of the relatively long lug adjacent its end opposite the 25 first lug, whereby the securing means will be protected on all sides by the outer solid walls of the lugs.

5. Connecting means for uniting the meeting ends of separate parts comprising a lug on each 30 of said parts adjacent the meeting ends thereof, one of said lugs being formed of material of substantial length secured throughout the length of one of its longitudinal sides to its respective part and having its other side walls formed continuous 35 and tapered from their ends adjacent the first lug toward their opposite ends wherein they blend into the part to which the lug is secured and means for securing the lugs together in aligned end to end relation with each other and with 40 their respective continuous side walls in substantially flush relation with each other to provide means on all sides for protecting the securing means.

EDWARD M. SPLAINE. 45
